JOHN V. TERRY, OF TUCSON, ARIZONA TERRITORY.

COMBINED FLUE EXPANDING, AND BEADING TOOL.

No. 829,303.

Specification of Letters Patent.

Patented Aug. 21, 1906.

Application filed April 10, 1906. Serial No. 310,904.

To all whom it may concern:

Be it known that I, JOHN V. TERRY, a citizen of the United States, and a resident of Tucson, in the county of Pima and Territory of Arizona, have made certain new and useful Improvements in a Combined Flue Expanding and Beading Tool, of which the following is a specification.

In practical service, especially in locomotive-boilers, the flues sooner or later become loosened in the head or flue sheet, so that leaks occur. In order to tighten the flues again and prevent leakage, their ends require to be expanded and also beaded or upset. It is the general practice to rely at first on beading or upsetting alone; but as the result of repeated operations of this kind the flue ends become what is termed "heeled"—that is to say, burred or roughened interiorly, and hence cannot be made to fit tightly as before. It is impossible to remove the bur and restore the flue to its proper place and fit without injuring it, and it is impossible to expand the flues with rollers owing to the burred or irregular inner surface, and hence resort is commonly had to a tapered expanding mandrel or "handle-pin," which when driven in is liable to force the bead away from the flue-sheet and cause it to break, thus destroying the usefulness of the flue.

My invention is adapted to perform both operations—to wit, expanding and beading simultaneously and in half the time required by the ordinary method, and the operation may be repeated as often as desired without destroying the flue.

The construction and operation of my improved tool are hereinafter described and illustrated in the accompanying drawings, in which—

Figure 1 is a central longitudinal section of the tool, a flue and flue-sheet being also shown in section. Fig. 2 is a plan view of the tool. Fig. 3 is a perspective view of one of the devices by which expanding and beading are effected. Fig. 4 is a cross-section on the line 4 4 of Fig. 1. Fig. 5 is a cross-section on the line 5 5 of Fig. 1.

The body A of the tool comprises an elongated cylindrical portion 1, that serves as a handle in operating the tool, and a head 2, which is slotted and enlarged laterally in opposite directions, also expanding and beading devices B, and a sliding hammer or piston C.

55 The body A of the tool is extended beyond the

slotted portion, or head 2, as indicated at 3, in Figs. 1, 2, and 5, such portion having a bead or enlarged circumferential rib 4, which enters the tube x, that is to be expanded and beaded.

The devices B are pivoted on bolts 5 in the outer portion of the slotted head 2, and the hammer or piston C is provided with an enlarged head 6, which is adapted to reciprocate in a correspondingly-enlarged chamber 65 of the handle 1. The head 6 of the hammer C strikes upon the anvil portion 7 of the devices B, thus tending to rotate them on their pivots 5, whereby the forwardly-projecting portions 8, that enter the flue, are caused to 70 act as hammers or levers, pressing outward against the inner side of the flue, thus expanding it corresponding to the force of the blow imparted to the hammer or piston C. Blows may be applied to the latter by a 75 hammer used manually or by a pneumatic hammer, or otherwise, as convenience may dictate.

As shown in Figs. 3 and 5, the outer sides of the hammer portions 8 of devices B are 80 rounded or curved, so as to conform practically to the curvature of the flues. At the base of the hammer portions 8 on the outer side thereof is formed a semicircular groove 9, by which the end of the flue is upset and 85 beaded, as indicated in Fig. 1. It will be noted that the pivots 5 of the devices B are located eccentrically with reference to the body of such devices—that is to say, the pivot-holes are located exterior to a plane coinciding with the axis of the hammer portion 8, and the anvil portions 7 are also located eccentrically to such plane, being on the inner side thereof, as will be seen by inspection of Figs. 1 and 3. In consequence of such location of the pivots and the anvil portions 7 95 and hammers 8 relative to each other it is apparent that the blow delivered by the piston C necessarily forces the hammers 8 apart and that a portion of the force thus applied is expended on the end of the tube x, thus gradually curving it outward and inwardly until its edge comes in contact with the flue, as shown in Fig. 1. Thus the operations of expanding and beading the flue ends are performed simultaneously and very expeditiously.

It is to be understood that in operating the tool it is rotated after each blow, so that the expansion and beading operations will be effected in such manner as to produce a smooth 110

surface without injuring the flue or defacing it in any manner.

As indicated in Fig. 1, the anvil portions 7 are rounded on their inner ends and inner sides, and thus adapted to work in contact under the impact of the piston C.

The body A of the tool is preferably made of forged steel and the other parts of tool-steel. The tool as a whole is light, strong, 10 and durable, may be cheaply constructed and easily manipulated, and is highly efficient in use.

I claim—

1. The improved flue-expanding and beading tool, comprising a tubular body having an enlarged slotted head, expanding and beading devices pivoted in said head and having hammer portions for expanding a flue and adjacent portions for beading the same, 15 and anvil portions located adjacently and opposite the inner end of the tubular portion, and a sliding piston or hammer adapted to act on such anvil portions, substantially as described.
2. The improved tool for the purpose specified, comprising a tubular body having an enlarged slotted head, and a tubular extension, or nose, 3, adapted to enter a flue, devices pivoted in the head and comprising 20 hammer portions for acting upon the flue for expanding it, and anvil portions located adjacently and opposite the inner end of the tubular portion, and a slideable hammer or piston adapted to act on such devices for rotat- 25 ing them and thus expanding a flue by impact of the hammer portions thereon, sub- stantially as described.
3. A tool for the purpose specified, comprising a tubular body having a slotted head, 30 flue-expanding devices pivoted in such head and having forward extensions adapted to enter a flue and act thereon by impact, anvil portions located contiguously at the opposite ends of the devices, and laterally from the 35 pivots of the latter and a slideable piston or

hammer that delivers blows on said anvil portions, substantially as described.

4. The combination with the tubular body of the tool, of a flue-expanding device pivoted thereto and having a hammer portion 50 projected forward, and an anvil portion projecting rearwardly and located inward from the plane of the axis of the hammer portion, and a slideable piston for acting on the anvil, substantially as described. 55

5. The combination, with the tubular body having a slotted head, of flue-expanding devices pivoted oppositely, and having hammer portions extended forward opposite each other, and anvil portions which are rounded 60 and adapted to work in contact, the same being located inward from the plane of the axes of the hammer portions, and a slideable piston for acting on the anvil portions, substantially as described. 65

6. The combination, with the tubular body having a slotted head, of flue-expanded devices having hammer and anvil portions located at opposite ends, and pivots located eccentrically to such hammer and anvil portions, and a slideable piston for acting on the anvil portions, substantially as described. 70

7. The combination, with a tubular body having a slotted head, of devices pivoted in such head and provided with grooves or recesses adapted to receive the end of a flue and upset and bead the same, and anvil portions arranged on the inner sides and outer ends of said devices, and a slideable piston for acting thereon, substantially as described. 75

8. The combination, with a body, and a slideable piston guided therein, of tube-expanding devices pivoted eccentrically to the body and having anvil and hammer portions at opposite ends, substantially as described. 80 85

JOHN V. TERRY.
